FRANK A. DECKER, OF PHILADELPHIA, PENNSYLVANIA, ASSIGNOR, BY MESNE ASSIGNMENTS, TO DECKER ELECTRICAL MANUFACTURING COMPANY, OF WILMINGTON, DELAWARE.

BATTERY.

No. 880,868.

Specification of Letters Patent.

Patented Feb. 25, 1908.

Application filed March 21, 1904. Serial No. 199,303.

To all whom it may concern:

Be it known that I, FRANK A. DECKER, a citizen of the United States, residing at Philadelphia, in the county of Philadelphia and State of Pennsylvania, have invented 5 certain Improvements in Batteries, of which the following is a specification.

This invention is designed to provide a compact battery cell having increased efficiency and decreased resistance, employing a construction for diaphragms or electrodes occupying comparatively little space and having comparatively large fluid contact surface, providing thin septa having ample 15 strength. The construction also provides means for the ready assemblage and dissociation of cells, and the ready introduction and removal of electrodes and excitants.

In the accompanying drawing illustrating 20 my invention, Figure 1 represents a face view of a plate or diaphragm embodying improvements thereof: Fig. 2 represents a sectional view taken on the line 2—2 of Fig. 1: Fig. 3 represents a face view of a plate or 25 diaphragm surrounded by a flange affording strength and entering into the formation of cup: Fig. 4 represents a sectional view taken on the line 4—4 of Fig. 3: Fig. 5 represents a face view of a second form of 30 diaphragm having bordering flanges: Fig. 6 represents a face view of a third form of flange bordered diaphragm: Fig. 7 represents a face view of a fourth form of flange bordered diaphragm: Fig. 8 represents a 35 fifth form of flange bordered diaphragm: Fig. 9 represents a vertical sectional view of a cup formed by joining right and left hand flange bordered diaphragms, the section representing a view taken on the line 9—9 40 of Fig. 8: Fig. 10 represents a perspective view of a cell construction, and Fig. 11 represents a perspective view of a second form of cell construction.

As shown in the drawings, the plate or 45 diaphragm 1 has recesses or glands 2 indented therein, the respective glands being separated from one another by the walls 3 and from the opposite sides of the plate by the walls 4. A large superficial area is thus 50 provided for each face of the plate and the walls may be made relatively thin, for facilitating the action, while maintaining ample strength. In the preferred construction the plates or diaphragms are thus honeycombed 55 in sections surrounded by the solid strips or

bands 5 which provide increased strength. This construction may be used for electrodes of carbon or other suitable material, or for diaphragms of clay or other suitable materials.

As shown in Figs. 3 to 9 inclusive, the plates or diaphragms may have bordering flanges 6 which provide additional strength and act in combinations to form cups.

As shown in Figs. 3, 5, and 8, the top of 60 the bordering flange may be provided with a gas vent 7. One of the upper corners may be provided with an aperture 7^a for the passage of a conduit 7^b which communicates with the interior of the cups 14, as by the 70 port 7^c, while the other of the upper corners may have the aperture 7^d which permits the flow of fluid between compartments on either side of the cells. One or both of the lower corners may be provided with an aperture or 75 apertures 8 for the passage of fluids.

As shown in Fig. 8, the upper flange 6 is provided with the aperture 6' which may be used for connecting a conductor to the plate when the latter is an electrode or for connecting a conductor with an electrode contained in the cup formed by joining together 80 porous earthenware plates.

It will be understood that the cup or compartment shown in Fig. 9 may be made of 85 porous earthenware for containing an electrode, or may itself be an electrode (of such material as carbon) containing a fluid depolarizer entering into the action of the cell.

As shown in Figs. 6, 7 and 8, one of the 90 passages 8 may be provided with a port 9 for communicating with a cup to be formed by means of the diaphragms, and the passages may be made in feet 10 for supporting the diaphragm.

As shown in Figs. 8 and 9, one of the lower 95 passages 8 may be connected by a channel 11 with a passage 12 having a port 13 adapted for communicating with the cup 14, the latter being formed by joining the flanged 100 borders of right and left hand constructions.

As shown in Figs. 10 and 11, the plates or diaphragms 1 may have the bordering flange 6 at the bottom and two sides and omitted from the top. The diaphragms may be 105 joined together to form cups 15 which may be spaced by guides 16 forming compartments 17, as shown in Fig. 10, or to form cups or compartments 18 by placing the diaphragms in series as shown in Fig. 11. The 110

cells formed as in Fig. 10 have the conduits 19 and 20 extending through the apertures 8 and the conduit 21 extending through the apertures 12. The conduit 19 has the orifices 19' communicating with the compartments 17, and the conduit 20 has the orifice 20' communicating by the port 9 with an end cup 15, which distributes to the several cups by the conduit 21 and the orifices 21' therein.

10 It will be understood that the several conduits 19, 20 and 21 are to be used for charging and withdrawing the fluids used in the several cups or compartments and that they are to be made of such section, length and 15 material as to provide the requisite electrical resistance to prevent leakage of current.

The diaphragms, assembled as in Fig. 11, have their passages 8 joined together to form conduits through the base of the cell, 20 the conduit having fluid connections by orifices, as 8^a, with the desired cups or compartments of the cell thus formed.

It is to be understood that the term "plate" as used in the claims is used in its 25 general meaning and is to be understood as having reference to an "electro-chemically active part," whether diaphragm or electrode, employing the characteristic idea of providing an extended fluid contact surface 30 within comparatively limited bounds. It is to be understood further that by the expression "electrochemically active part" is to be understood that the part referred to has an active function, as the function of an electrode or a diaphragm, in the electro-chemical 35 scheme, and is to be distinguished from the electro-chemically passive cellular structure for holding lead or like material that is to enter into the electrochemical action.

40 Having described my invention, I claim:—

1. In an electrochemical apparatus, an electrochemically active part having a honey-combed construction on each side thereof providing a comparatively larger fluid contact surface within comparatively limited borders, substantially as specified.

45 2. In an electrochemical apparatus, a plate having overlapping indentations in its opposite sides, substantially as specified.

3. In an electrochemical apparatus, a 50 plate having a group of indentations in each side thereof and unindented strips adjacent thereto, substantially as specified.

4. In a battery, a diaphragm having a bordering flange and a honeycombed body, sub- 55 substantially as specified.

5. In a battery, a cell comprising a pair of diaphragms one of which has a bordering flange and a honeycombed body, substan- 60 tially as specified.

6. In a battery, a cell comprising a plu- 65 rality of diaphragms each of which has a bordering flange and a honeycombed body, the bodies and flanges of said diaphragms being joined together to form fluid recepta- cles, substantially as specified.

7. In a battery, a cell comprising a plu- 70 rality of diaphragms having bordering flanges, passages transverse to said dia- phragms through said bordering flanges, and a conduit passing through said passages, substantially as specified.

8. In a battery, a cell having comp- 75 artments comprising a plurality of diaphragms having bordering flanges, a plurality of pas- sages transverse to said diaphragms through the flange of each of said diaphragms, and a plurality of conduits passing through said passages and communicating with said com- partments, substantially as specified.

9. In a battery, a cell comprising a plu- 80 rality of diaphragms having bordering flanges, and a transverse passage through the flange of each of said diaphragms, substan- tially as specified.

10. In a battery, a diaphragm having a bordering flange, a transverse passage through said flange, and an orifice communi- cating with said passage, substantially as 85 specified.

In testimony whereof I have hereunto set my hand this 18th day of March, A. D. one thousand nine hundred and four in the presence of the subscribing witnesses.

FRANK A. DECKER.
